Primary Examiner — Mary Ann Calabrese*Assistant Examiner* — Jennifer L Rempfer(74) *Attorney, Agent, or Firm* — Dunlap Bennett & Ludwig PLLC(57) **CLAIM**

The ornamental design for a baby blanket, as shown and described.

DESCRIPTION

FIG. 1 is a front perspective view of a baby blanket;
 FIG. 2 is a front elevation view thereof;
 FIG. 3 rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof; and,
 FIG. 8 is a perspective view thereof, with the pockets of the
 baby blanket shown in an open configuration.
 The broken lines along the open edge of the pocket form no
 part of the claimed design.

1 Claim, 5 Drawing Sheets(56)
